UNITED STATES PATENT OFFICE.

WILFRID THOMAS REID, OF BRISTOL, ENGLAND, ASSIGNOR TO THE BRITISH & COLONIAL AEROPLANE COMPANY LIMITED, OF BRISTOL, ENGLAND.

INTERNAL-COMBUSTION ENGINE.

1,318,409.

Specification of Letters Patent.

Patented Oct. 14, 1919.

Application filed July 17, 1918. Serial No. 245,376.

To all whom it may concern:

Be it known that I, WILFRID THOMAS REID, a subject of the King of England, residing at Bristol, England, have invented certain 5 new and useful Improvements in Internal-Combustion Engines, of which the following is a specification.

This invention relates to internal-combustion engines.

10 The object of the present invention is the construction of an internal-combustion engine wherein the auxiliaries can be actuated by very simple gearing and wherein they can be conveniently arranged and can have their 15 weights and their bulk symmetrically disposed at opposite sides of the longitudinal center-line of the engine.

According to the present invention there is combined with an engine of the type in 20 which the main drive is taken from a principal single or twin gear-wheel in the middle of the crank-shaft, a subordinate gear-wheel also in or about in the middle of the length of the crank-shaft, and to this subordinate 25 gear-wheel (or instead, if desired, to the main gear-wheel or one of them) is geared a series of secondary shafts. The secondary shafts are parallel to one another, and lie one above another, and preferably in a vertical plane common to them all, and they are all transverse to the engine crank-shaft, and are supported in bearings in the engine. They are geared to the engine crank-shaft. One of them may be above that crank-shaft, 30 and geared directly by a helically-toothed gear-wheel on that secondary shaft to another helically-toothed gear-wheel at right-angles to it and fixed on the engine crank-shaft. Another of the secondary shafts 35 (herein for convenience alluded to as the second) may be immediately below the engine crank-shaft, and can similarly gear directly with the helically-toothed wheel on the latter.

40 A third shaft of the secondary shafts may be below the second and there may be a fourth and fifth below the third. Of the third, fourth and fifth secondary shafts each has a helically-toothed wheel fixed upon it; 45 that on the fifth is in the same plane as and gears directly with that on the fourth, while that on the fourth is in the same plane as and gears directly with that on the third, and that on the third is in the same plane as

and gears directly with that on the second. 55 Thus there need be only six gear-wheels for the five secondary shafts, *i. e.* five on those shafts and one on the crank-shaft.

The accompanying drawings illustrate an internal-combustion engine with the present 60 invention applied thereto. In these drawings—

Figure 1 is a longitudinal section of the engine, and

Fig. 2 is a transverse vertical section of 65 Fig. 1; as to the left-hand half of Fig. 2 it is a section through one of the cylinders in Fig. 1, and as to the right-hand half it is a section through the middle of Fig. 1.

In the engine illustrated the main drive is 70 taken from a twin gear-wheel GW in the middle of the crank-shaft CS. A subordinate gear-wheel SGW is in the middle of the length of the crank-shaft being an integral part of the boss *gw* of the twin gear-wheel GW which is a virtual continuation 75 of the crank-shaft from one set of cranks C C C to the other set of cranks C¹ C¹ C¹. To this subordinate gear-wheel is geared a series of secondary shafts 1, 2, 3, 4, 5. The 80 secondary shafts are parallel to one another and lie above one another in a vertical plane common to them all and transverse to the engine crank-shaft CS; they are supported in bearings *b* in the engine. One shaft, 1, is 85 above the engine crank-shaft and geared directly by a helically-toothed gear-wheel 1^a on that secondary shaft to a helically-toothed gear-wheel SGW at right angles to it and fixed on the engine crank-shaft or 90 on a piece inserted in the middle of the engine crank-shaft; in the present example it is fixed on the sleeve *gw* of Fig. 1. The secondary shaft 2 is immediately below the engine crank-shaft and is similarly geared 95 directly with the helically-toothed wheel SGW on the latter by means of a helically-toothed wheel 2^a fixed on the shaft 2.

A third secondary shaft 3 is below the second and geared to the wheel 2^a on the 100 second shaft by the wheel 3^a on the third shaft. Below the third shaft is a fourth secondary shaft 4, geared by a wheel 4^a fixed upon it to the wheel 3^a of the shaft 3 above, and geared below to a fifth secondary shaft 105 5 by the wheel 5^a fixed to the latter.

At each end of the secondary shaft 1 is a magneto M, only one of these magnetos be-

ing shown in the drawing. At each end of the secondary shaft 2 is a gear-wheel 2^b (only one end of the secondary shaft being shown in the drawing, the other end being 5 identical); each end of the shaft 2 directly drives centrally the engine cam-shafts ECS.

The third secondary shaft 3 has at each of its ends a water-circulating pump P. The fourth secondary shaft is an idler. The 10 fifth secondary shaft has at its opposite ends the two related parts of a lubricating-pump, one part, a suction-device SD, drawing from the sump S, and the other part, a pressure-device PD, delivering into the lubrication 15 circulation-system. The fifth shaft is geared through the wheel 5^a fixed to it, with the shaft 3 by way of the idler 4^a on shaft 4.

The construction illustrated for driving centrally from the main crank shaft is 20 claimed in my copending application, Serial No. 249,023, filed August 8, 1918.

What I claim as my invention and desire to secure by Letters Patent is:—

1. In an internal combustion engine, the 25 combination with a crank shaft having a main driving gear wheel, of a subordinate gear wheel adjacent thereto, a series of secondary shafts extending transversely to said crank shaft and symmetrically on opposite 30 sides of the engine, a secondary gear wheel mounted centrally on each of said secondary shafts and geared with said subordinate gear wheel, and auxiliary devices arranged in pairs with one device of each pair 35 at opposite ends of each of the secondary

shafts and on opposite sides of the engine, substantially as described.

2. In an internal combustion engine, the combination with a crank shaft having a 40 main driving gear wheel in the middle thereof, of a subordinate gear wheel on the crank shaft adjacent thereto, a series of secondary shafts extending transversely of the crank shaft and symmetrically on opposite sides of the engine, secondary gear wheels mounted 45 one on the central part of each secondary shaft and intergeared with one another and with said subordinate gear wheel, and auxiliary devices arranged in pairs with one device of each pair at opposite ends of each 50 of the secondary shafts on opposite sides of the engine, substantially as described.

3. In an internal combustion engine of the character described, the combination with a crank shaft of a main driving twin gear 55 wheel in the middle thereof, a subordinate gear wheel intermediate the parts of said twin gear wheel, a series of secondary shafts arranged transversely of the crank shaft and extending symmetrically on opposite sides 60 of the engine, secondary gear wheels mounted one on the central part of each secondary shaft and driven from said subordinate gear, and auxiliary devices arranged in pairs of similar devices, one at each end of each 65 secondary shaft and on opposite sides of the engine, substantially as described.

In testimony whereof I affix my signature.

WILFRID THOMAS REID.
